TOILET

Emory C. Williams, Fort Payne, Ala.

Application June 29, 1945, Serial No. 602,268

5 Claims. (Cl. 4—10)

1

This invention relates to toilets, one of the objects being to provide a toilet hopper so constructed that it can be concealed in the wall of a room, where it is made readily accessible by the use of a simple and compact mechanism under the control of a closure in the wall, thereby eliminating the use of floor space which thus is made available for other purposes.

It is another object of the invention to provide a movably supported hopper which is equipped with all necessary flushing, draining and ventilating means whereby the structure is rendered no less sanitary than the usual toilet equipment.

A still further object is to provide a structure designed especially for use in partition walls between adjoining rooms, access being had thereto through a door opening leading from each room, the mechanism employed being such that when one of the doors is moved to open position, the opposed door locks automatically and the hopper brought into position for use.

Another object is to provide means whereby movement of the hopper into active position and subsequent return thereof to its normal or housed position, will effect automatically thorough flushing of the hopper.

A still further object is to provide a structure wherein both doors leading thereto are free to be opened separately when the hopper is stored in its housing but when one of the doors is moved from its closed position, the other door is automatically locked in closed position so that access to the hopper can be had only from one of the adjoining rooms at the same time.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a horizontal section through a partition equipped with the present improvement, one door being shown by full lines in open position and by broken lines in closed position and the other parts of the structure being similarly illustrated.

Figure 2 is an elevation of the structure shown in Figure 1, the open door being illustrated in

2

section taken substantially on the line 2—2, Figure 1.

Figure 3 is a section on line 3—3, Figure 1, the hopper being in its open position.

Figure 4 is a section on line 4—4, Figure 3.

Figure 5 is a horizontal section through portions of the closed doors and illustrating, in top plan, the connections between the hopper and the two doors when the doors are in their normal or closed positions.

Figure 6 is a section on line 6—6, Figure 5.

Figure 7 is a view similar to Figure 6 and showing the relative positions of the door and hopper connections when one of the doors is unlatched preparatory to being opened.

Figure 8 is a section on line 8—8, Figure 4.

Figure 9 is a section on line 9—9, Figure 3.

Figure 10 is an elevation of a portion of one side of a partition through which a portion of the indicator is displayed.

Figure 11 is an elevation of a portion of the opposite side of the partition showing a portion of the indicator.

Referring to the figures by characters of reference, 1 designates a portion of a partition separating two rooms of a structure and within this partition, at a proper distance from the floors of the rooms, is a compartment 2 proportioned to receive the apparatus constituting the present invention. This compartment is open at both sides so that access can be had thereto from either room, and each side is normally closed by a hinged door. The two doors have been indicated at 3 and 4 respectively. The hinges 5 of the doors are located at the same end of the compartment.

Slidably mounted in the compartment at the other end thereof is a transverse slide 6 which can be provided with slots 7 for the reception of guide screws 8 or the like. The ends of this slide are pointed as shown at 9 and when the two doors 3 and 4 are closed, as shown in Figure 8, these pointed ends 9 are seated in tapered recesses 10 formed in pins 11. One of these pins is slidably mounted in each door 3 and 4 and is held normally pressed toward the slide 6 by spring 12. The movement of each pin 11 under the action of its spring is limited by a finger 13 carried by the pin and having a terminal lug 14 extended in the direction in which the pin moves under the action of its spring 12. This finger and its lug are adapted to move against disk 15 seated in the door and rotatable with the shank 16 of a door handle 17 supported outside of the door. The disk 15 carries an ear 18 so located that when

the disk 15 and shank 16 are turned in one direction, after the door has been closed, the ear will move behind a keeper 19 extending from the open side of the compartment 2, the door being recessed, as at 20 to receive this keeper when the door is closed.

From the foregoing, it will be obvious that when the two doors are closed and the handles 17 turned to their proper positions, the ears 18 will be in engagement with the respective keepers 19 so that the doors will remain closed. However, when one of the handles is turned in one direction to swing the ear 18 out of engagement with its keeper, thereby to release the door so that it can be opened, the door is swung to open position and thus immediately withdraws the pin 11 in the said door from engagement with the pointed end 9 of slide 6. Consequently, the spring pressed pin 11 in the other or closed door will advance, thereby causing the lug 14 on the advanced pin to enter the recess 20 provided therefor in the adjacent disk 15. Thus the handle of the closed door cannot be turned and said door remains locked. However, when the door which had been opened is moved back to closed position, the pin 11 carried thereby will come against the pointed end of slide 6 so as to thrust the slide against the other pin 11 and cause the lug on the finger of the shifted pin to become disengaged from disk 15. Thus both handles are released for rotation.

A window opening 21 can be located in the partition above each of the doors 3 and 4 and a drum 22 can be mounted for rotation between these openings. This drum is mounted for rotation and has a pin 23 therein which is off center and is constantly engaged by an actuating arm 24 which is extended upwardly from and moved with the slide 6. Thus, when the slide is moved in one direction, the drum is rotated in one direction but when the slide is moved in the opposite direction, the movement of the drum is reversed. Suitable indications can be carried by the drum and displayed through the respective openings, as shown at 25 so that when both doors are closed that fact will be indicated within the two openings 21. When one of the doors is open, the indication appearing in the window opening at the opposite side of the partition will be changed to show that the toilet is in use. In order that the rotation of the drum back and forth to its different positions may not be interfered with by the arm 24, an opening 26 is provided in the drum and the arm 24 is extended loosely therethrough.

A stationary soil pipe 27 is extended upwardly through the floor of the compartment 3 adjacent to one side of the compartment but at a point midway between the two doors when closed. Mounted for rotation in the upper end of this soil pipe is the lower end portion of a pipe section 28 which can be made integral with the back portion of a hopper 29 opening thereinto at a point where the contents of the hopper can be flushed into the pipe section 28 and the soil pipe 27. The joint between pipe section 28 and soil pipe 27 is suitably backed, as at 30, so as to prevent leakage of gas or moisture, and the upper end of the pipe section is flared as shown at 31 so as to provide a tight seat for a tapered extension 32 on the bottom of a valve casing 33. This valve casing is suitably mounted above the level of the door openings and is held securely to the pipe section 28 by a tubular coupling member 34 fitted snugly in the upper portion of the pipe section 28 and secured thereto in any suitable manner, as by means of bolts 35. Annular shoulders 36 are

formed on the upper portion of the tubular couplings and engage seats 37 in the tapered extension 32 so that when the coupling is secured in position, the valve casing 33 is held securely assembled with the pipe section 28 but said pipe section can rotate relative thereto.

The valve casing 33 has a water inlet compartment 38 with which communicates a feed pipe 39. An intermediate compartment 40 is connected by 10 a pipe 41 to a tank 42 located thereabove. An outflow compartment 43 is also provided in the casing 33 and is adapted to open downwardly into the tubular coupling 34. A slide valve 44 is mounted in the compartment 43 and has a V-shaped 15 groove 45 in the bottom thereof into which extends an actuating pin 46 projecting upwardly from the coupling 34.

As the hopper 29 swings into and out of the compartment 2 the pipe section 28 and the coupling tube 34 are caused to move therewith and the pin 46 and the groove 45 are so positioned that when the hopper is located between the closed doors, the pin 46 is located at the center or apex of the groove 45 with the result that slide 44 is shifted to the left in Figure 3 so as to open communication between compartment 43 and the interior of the pipe section 28. However, when the hopper is swung outwardly into operative position, the parts are brought to the positions shown in Figure 3 with the result that the slide or valve 44 is shifted by pin 46 to close communication between compartment 43 and the pipe section 28. This position of the pin has been shown both in Figures 3 and 9.

35 A stem 47 is secured to and moves with the slide valve 44 and is provided with two valves 48 and 49 respectively. One valve is so located as to close communication between the compartments 40 and 43 when slide valve 44 is in closed 40 position, as in Figure 1, and at the same time valve 49 is in open position within compartment 38. Thus when the hopper is in use, water is free to flow from pipe 39 into compartment 38 and thence into compartment 40 through pipe 41 to tank 42, thereby filling the tank. When the hopper is swung back into the space between the closed doors, thereby sliding the valve 44 away from the position shown in Figure 3 and establishing communication between compartment 43 and pipe section 28, the valve 48 is open and at the same time valve 49 is moved into position to close communication between the compartments 38 and 40. Thus the flow of water to the tank 42 is cut off and at the same time the water already stored in the tank is released to flow by gravity into compartment 40 and thence to compartment 43 and downwardly through the tubular coupling 34 into the hopper at any suitable point and thence outwardly from the hopper 55 into the pipe section 28 to the soil pipe. The outlet from the tank into the hopper 29 has been indicated at 50 in Figure 1.

It is to be understood, of course, that the hopper, which opens in the usual way into the soil pipe, is to be of such a construction as to provide the requisite water seal against the escape of gases from the soil pipe into the hopper, and has not been shown in detail.

Extending downwardly from the bottom of the hopper 29 at a point remote from its axis of rotation, is a pivot pin 52 on which is mounted one end of a link 53 which can be held in position on the pin by any suitable means, such as a nut 54. This link has a flat head 55 at a free end and lying 70 in a plane at right angles to the axis of movement

of the link. The head 55 consists of oppositely extending ears 56 and 57 and in each ear is located a circular opening 58. The two ears have arcuate edges 59 concentric with the opening 58 and terminating in shoulders 60. The shoulders are extended inwardly to arcuate edges 61 concentric with the opening 58 and merging into the respective sides of the link 53 as shown, for example, in Figure 1.

When the hopper is housed within compartment 2 as shown by broken lines in Figure 1, the link 53 is extended toward the axis of movement of the hopper with the ears 56 and 57 extended toward the respective doors 3 and 4.

Mounted for up and down sliding movement on each door is a coupling bracket 62 having slotted portions 63 mounted on guide screws 64 or the like engaging the doors. Each of these coupling brackets is pivotally engaged by one end of a bell crank 65 fulcrumed at 66 on the inner side of the adjacent door and having its other end pivotally connected, as at 67 to the adjacent handle operated disk 15. Thus when the handle 17 of one of the doors is rotated for the purpose of disengaging ear 18 from its keeper 19, the bell crank 65 is shifted to raise the coupling bracket 62 connected thereto.

Each coupling bracket has an arm 68 which extends inwardly from the door and is normally positioned beneath one of the ears 56 and 57. On each of these arms 68 there is an upstanding pin 69 and when the parts are in their normal positions with the doors closed, these pins are located directly under the respective openings 58 so that when one of the coupling brackets is raised, the pin carried by that bracket will be lifted into the opening and form a pivotal connection between the bracket and the ear 56 or 57 in which the pin is located when raised.

A keeper in the form of an angular stud 70 is extended upwardly from the arm 68 of each bracket and when the hopper is housed between the closed doors, this stud is located beyond the adjacent shoulder 60 and outwardly from the adjacent arcuate edge 61. Thus when the coupling bracket is lifted as explained so as to insert its pin 69 into opening 58, the angular stud 70 can move upwardly relative to the engaged ear. Consequently, when the door is swung outwardly and the relative position thereof with respect to the hopper is changed, the upper end portion of the angular stud will move into position past the adjacent shoulder 60 so as to overlie the arcuate edge 59 as shown, for example, in Figure 1. Consequently, with the parts thus located, the engaged ear on the link 53 cannot be lifted off of the pin nor can the bracket 62 be lowered away from the ear. Instead, the two parts will be positively coupled until the hopper is returned to its housed position with the door closed.

It has already been explained how the doors can be separately unlocked. This unlocking operation, as has also been explained, will result in raising the coupling bracket 62 carried by the door to be opened so that the pin on said bracket will enter the opening 58 in the ear located thereover. When the door is moved forwardly the link will swing therewith so that the overhanging portion of the stud 70 will ride onto the engaged ear and the continued movement will result in the link 53 pulling the hopper around about its axis of rotation until it is positioned outside of the compartment 2 with the door at one side and wide open. At this time, the other door cannot be opened.

When it is desired to return the hopper to its housed position, the foregoing operation is reversed and when the door is completely closed and the handle is turned to fasten it in closed position, the coupling bracket carried by said door will move downwardly, thereby withdrawing its pin 69 from the opening 58 and permitting the angular stud 70 to move downwardly past the shoulder 60. Thus both doors are uncoupled from the hopper but the coupling brackets of both doors are positioned where either one of them can be brought into engagement with one of the ears for the purpose of coupling the hopper to that particular bracket and the door on which the bracket is mounted.

As before explained, when the hopper is swung outwardly from compartment 2, the water in pipe 39 is released by valve 49 so as to flow into and fill the tank 42. When the hopper is swung back to housed position, this water contained in the tank is released to flow into the hopper and thence outwardly to the soil pipe 27.

Obviously, the doors can be suitably recessed, if necessary, and as shown at 11, so as to increase the capacity of the compartment 2 and thus permit the use of a hopper of greater width than otherwise could be employed.

Any suitable means may be employed for ventilating the hopper while housed in compartment 2 and also while extended from the housing. Inasmuch as the ventilating means constitutes no part of the present invention, no effort has been made to disclose it.

It is to be understood, of course, that the construction of the lock can be modified, if desired, it merely being essential that means be employed whereby when both doors are closed, either one of them can be easily unfastened and opened but when one of them is moved from closed position, the other door is automatically locked against movement.

It is to be understood that any suitable means may be provided whereby a portion of the mechanism can be disengaged to permit one of the doors to be opened without actuating the hopper, so that access may be had thereto.

While the flared portion 21 can constitute a seal or seat, it is to be understood that it is especially useful as a means for trapping any liquid that might leak past the seats 36-37, in which case the parts would not be fitted together tightly at 31 and 32 and moisture draining into the flared end could be carried off through one or more small apertures 34' provided for that purpose.

What is claimed is:

1. The combination with a structure having a compartment therein, said structure having opposed openings, of a door for each opening, a hopper supported for movement about an upwardly extending axis into and out of position within the compartment and normally concealed by the doors, locks for fastening the respective doors in closed positions, a link pivotally connected to the hopper, slideable elements on the doors operatively connected to and shiftable by the respective locks, pivot devices on said elements positioned for engagement with the link when the respective elements are actuated, each door, when coupled to the link by the pivot device carried by said door, constituting means for shifting the hopper about its axis out of or into the compartment when the door is opened or closed respectively.
2. The combination with a structure having a

compartment provided with openings at opposite sides thereof and a door for closing each opening, of a hopper mounted for swinging movement into and out of the compartment through either opening, a link pivotally connected to the hopper, a coupling bracket slidably mounted on the door and having a portion normally positioned under the link, fastening means on each door, means actuated by the operation of either fastening means for shifting its coupling bracket relative to the link, means on the bracket for pivotally engaging the link when the bracket is shifted, thereby to couple the link to the bracket, for actuation by the door.

3. The combination with a structure having a compartment provided with openings at opposite sides thereof and a door for closing each opening, of a hopper mounted for swinging movement into and out of the compartment through either opening, a link pivotally connected to the hopper, a coupling bracket slidably mounted on the door and having a portion normally positioned under the link, fastening means on each door, means actuated by the operation of either fastening means for shifting its coupling bracket relative to the link, means on the bracket for pivotally engaging the link when the bracket is shifted, thereby to couple the link to the bracket, for actuation by the door, and means on each bracket and cooperating with the link for holding the bracket against disengagement from the link when the door is open.

4. The combination with a structure having a compartment provided with opposed openings, and a door for each opening, of a fastening device on each door, a coupling bracket slidably connected to each door, means actuated by each fastening device for shifting the coupling bracket relative to the door, a hopper mounted to swing into and out of the compartment about an upwardly extending axis, a link pivotally connected to the hopper, means on the link normally lap-

ping the respective brackets when the doors are closed, cooperating means on the brackets and the links for pivotally coupling either bracket to the link when said bracket is shifted from normal position, thereby to couple the links to one of the doors for actuation by the door.

5. The combination with a structure having a compartment provided with opposed openings, and a door for each opening, of a fastening device on each door, a coupling bracket slidably connected to each door, means actuated by each fastening device for shifting the coupling bracket relative to the door, a hopper mounted to swing into and out of the compartment about an upwardly extending axis, a link pivotally connected to the hopper, means on the link normally lapping the respective brackets when the doors are closed, cooperating means on the brackets and the links for pivotally coupling either bracket to the link when said bracket is shifted from normal position, thereby to couple the links to one of the doors for actuation by the door, and means carried by each bracket and shiftable into engagement with the link when the bracket is moved from normal position, for holding the link in engagement with the bracket when the door is open.
